PROCESS FOR THE TREATMENT OF PATENT
FLAT STOCK AND LOW GRADE

Iver P. Schei, Fergus Falls, Minn.

Application October 10, 1936, Serial No. 105,124

2 Claims. (Cl. 83—42)

The object of my invention is to provide a novel flat stock reducer for the process or treatment of patent flat stock and low-grade flat stock; to devise a novel arrangement of a leather-covered roller and a novel leather-covered concave plate cooperating with the roller and freely suspended by pintles to provide a greatly increased contact surface for effecting a gentle pulling action on the product as it passes through the machine; to devise a new addition to milling by a machine such as I have devised; and to provide various details of improvement in connection with the structure of the machine.

It is also an object of my invention to provide a machine which will leave the flour particles round and sharp instead of soft and will leave the delicate and essential flour cells intact, and to give better action in dough fermentation through uninjured cells, thereby producing a better loaf of bread; which will increase profits through increased patent production from three to ten per cent, or 6¢ per barrel in the average mill.

I attain these and other objects of my invention by the mechanism illustrated in the accompanying drawings, in which—

Figure 1 is a vertical section through my machine.

Fig. 2 is a transverse section through the roller and plate;

Fig. 3 is a side elevation of the roller, a portion of the shaft 7 being broken away for lack of space;

Fig. 4 is a front elevation of the plate 13 detached from the machine.

Fig. 5 is an end elevation of plate 13 and member 16; and

Fig. 6 is an end elevation of roller 9 and shaft 7. Like numerals designate like parts in each of the views.

Referring to the accompanying drawings, I provide a casing 1, having a suitable door 2. Casting 1 has a feed hopper 3 at the top and a suitable feed roller 4 in the path of the feed hopper. A suitable adjustable gate 5 regulated by suitable adjusting means 6 is arranged adjacent to feed roller 4 to allow the product to pass between it and the feed roller as shown in Fig. 1.

Spaced a suitable distance below roller 4, I arrange a shaft 7 on which is mounted a hub 8 carrying a substantially hollow roller 9 which has a double leather (or a suitable nonmetallic, flexible rubber or composition) covering 10 secured to its surface by suitable means, as by bolts 11 and locknuts 12, as shown in Fig. 3. I have

devised a novel concave plate 13 which is provided with adjustable and removably mounted pintles 14 extending horizontally from the upper end portions of the plate, as shown in Figs. 4 and 5, for pivotally mounting the plate in the 5 casing. Attached to the lower end of the plate 13 is a bar 18 connected to the hooked end of the rod 19, which is mounted on a suitable bracket 22 and maintained in the desired adjusted position by means of a coil spring 20 and 10 thumb nut 21. The function of this device is to regulate the distance of the leather-covered surface of the concave plate 13 from the leather-surface 10 of the roller 9. The concave surface of plate 13 is about $\frac{1}{16}$ " to $\frac{1}{32}$ " of an inch spaced 15 from the surface of roller 9 when the machine is in operation.

The plate 13 is recessed as shown to receive the strips of leather (or other flexible, non-metallic composition) 16 of suitable thickness, preferably 20 $\frac{1}{2}$ to 1 inch in thickness. Any suitable number of screws or bolts 11 may be provided to secure the leather covering 10 to the surface of the metal roller 9. A leather (or other non-metallic composition) 16 is dovetailed into the casting, as 25 shown in the drawings as this is necessary to hold the upper edge of the leather, the dovetailing together with the bolts holding it from slipping away from the dovetailed portion of plate 13. Roller 9, as shown in Figs. 2 and 3, is substantially hollow. By using the bolts 11 which do not project clear through the leather covering 10, I avoid any hard projections on its surface such as rivets or bolts to injure the leather or composition 30 of the concave strip 16.

The mode of operation or process of this reducer is that instead of churning the flour and thereby pulverizing it, this machine gently pulls or combs the flour from the fiber, and thereby it is able to produce a round and sharp granulation, so much so that the sharpness of the entire 40 patent stream may be noted. The chief element or idea back of this new reducer is that of leather working against leather under a concave system, giving $3\frac{1}{2}$ " of contact, producing flour carrying 45 less ash and more protein. The product passes between the leather-covered (or flexible composition) surface 10 of roller 9 and the concave leather-covered (or flexible composition) surface 16 of plate 13. The double leather covering 10 of 50 the roller 9 and the leather lining 16 of plate 13 have a tendency to hold fast to the woody fibers, giving the roller a chance to pull the flour off the fibers.

By using the novel concave plate I obtain a 55

greatly increased contact or operating surface over that obtained by two rollers, thereby eliminating need of heavy contact, with resultant friction, and therefore do not require one-tenth 5 of the power that rollers require to accomplish what the miller wants and needs.

The plate 13 is not held rigid, but has support, for steadyng purposes, to keep it from bobbing back and forth. This support comes in the form 10 of the bar 18 or rod 19 adjusted by spring 20 and nut 21, whereby the lower end of the plate 13 and its covering 16 is gently pressed toward the roller, the theory being that the smaller the feed volume passing through, the more this portion 15 of the machine will have to press up.

It will be noted that a portion 17 of the plate 13 overlaps the upper edge of the leather or composition concave strip 16. The reason for this is to overcome an electric arc set up by the movement of the roller. If the leather extended higher up, the arc would cross from one covering 20 or composition to the other too early and thus check the feed flow on its way down to the pulling point.

In using this machine to treat the product known as flat patent stock the method of operation above described is followed. The most desirable point of installation for the treatment of 25 patent flat stock is on the last middling. It may be used on flat stock such as that which passes through the last flour cloth of the bottom sieve of the sifter by using No. 8 cloth. It will work nicely on stock from smooth rolls used in reducing No. 1 and No. 2 middlings, after it leaves 30 the rolls and before reaching the reel or sifter. It will increase the bolting capacity. In any mill where the system includes taking stock off a No. 8 cloth, where the product going through it is flat, treatment by this machine will be found 35 desirable as well as profitable. It should be noted that you can always use a cloth about one number coarser by the use of this machine than in the use of any other or rolls. The stream is not sent through a reel afterward but continues 40 on its present regular course to the sifters. It merely replaces any other machine now being used, with the following advantages: Where machines of the prior art do more or less grinding or 45 churning and thereby pulverizing the flour and reduce the quality of the flour by injuring the flour cells, my machine confines its operations to pulling and thus preserving, through leaving the flour cells undisturbed, the highest possible 50 quality in the flour. These uninjured flour cells enter into a more nearly correct action of the dough in fermentation. Moreover, this ma-

chine nearly doubles the bolting capacity of any other machine now being used for the same purpose.

In using this machine to treat the product known as low grade, that is, the material between the regular flour and the shorts, I take the product and pass it through the machine, then through a revolving reel, and extract a very satisfactory flour from it that will enter into what is called first clear, which means the third grade 10 of flour. I have obtained laboratory tests from that operation which showed a better flour with a difference of three fractions in ash and 1 1/2 points in protein. The protein is a helper for a larger loaf and three fractions less of ash helps 15 the color and indicates a flour of higher quality than that from the previous reduction.

I do not claim to do away with the roller mill. I am using this machine for removing fibers from the product, so that it can more easily pass 20 through the silk meshes and tail off the impurities. In milling we have to look out that we do not get too much of what is called ash into the flour. By using this machine I have less ash after my operation than in the stream ahead of 25 my machine that I am taking my supply from; and comparing those two flours, my machine obtains a more desirable proportion of ash and protein.

This application is a continuation in part of 30 my application Serial No. 749,999, filed October 25, 1934, which has since become abandoned.

What I claim is:

1. A process for the treatment of what is known in milling as patent flat stock and low 35 grade, comprising feeding the flat stock and low grade in regulated quantities between coacting moving and stationary leather covered surfaces, and applying controlled pressure to the flat stock and low grade while moving between said surfaces to effect a mild and pulverizing action on 40 the woody fibers of the wheat, to separate said fibers and the flour particles ready for the reel.

2. A process for the treatment of what is known in milling as patent flat stock and low 45 grade, comprising feeding said wheat products by gravity in regulated quantities between co-acting moving and stationary non-metallic surfaces, and applying a sufficiently limited degree 50 of regulated pressure to the flat stock and low grade while moving between said surfaces to effect a mild and non-pulverizing action to gently pull the flour of the fibers from the flour particles and leave the flour cells intact, as described in the foregoing specification.

IVER P. SCHEI.
